WITNESS:

UNITED STATES PATENT OFFICE.

ELBERT E. RICKS, OF PHILADELPHIA, PENNSYLVANIA.

SNOW-REMOVING MACHINE.

1,408,471.

Specification of Letters Patent. Patented Mar. 7, 1922.

Application filed May 15, 1920. Serial No. 381,619.

To all whom it may concern:

Be it known that I, ELBERT E. RICKS, a citizen of the United States, residing at Philadelphia, in the county of Philadelphia and State of Pennsylvania, have invented new and useful Improvements in Snow-Removing Machines, of which the following is a specification.

This invention relates to snow removing machines and it has more particular reference to that type or form of machine which is provided with heating means whereby the snow can be rapidly melted and allowed to run to waste, and it has for 10 its main object to provide a machine of the kind referred to whereby the snow can be rapidly reduced to a liquid condition and permitted to flow to the gulleys or sewers whilst the operation of reduction is 15 taking place.

Another object of this invention is to provide a snow removing machine which ejects live steam on to the snow whereby a much more rapid dissolution thereof takes 20 place and the work of cleaning it away is greatly expedited.

A further object of the invention is the provision of a snow removing machine which can be promptly adjusted to accommodate streets or highways of different widths and which furthermore can be conveniently adapted for service as a self-propelled or otherwise driven machine.

Still further this invention aims to provide a simple and very effective snow removing machine which can be constructed and maintained at small comparative cost.

With the foregoing and other objects in view as will later on more fully appear, my 40 invention comprehends a transportable vehicle which is provided with foldable or collapsible side and end snow reducers or dissolving means for supplying live steam to said reducers and ejecting same onto the 45 snow to be melted and means for raising the reducers independently or simultaneously into folded or collapsed position.

In the further disclosure of the invention reference is to be had to the accompanying sheet of explanatory drawings constituting a part of this specification, and in which like characters of reference designate the same or similar parts in all the views.

Figure 1 is a plan view of one convenient 55 form of my improved snow remover and as adapted for attachment as a trailer to a self propelled vehicle.

Figure 2 is a side elevation of the same taken substantially on the line 2—2 in Figure 1.

Figure 3 is an enlarged fragmentary detail of one of the guiding members for the reducers proper; and

Figure 4 is a sectional plan taken approximately on the line 4—4 in Figure 3.

Referring more particularly to the drawings, the numeral 10 designates a platform or truck body appropriately mounted on road or track wheels 11 and adapted for connection by a draw bar 12 to a self-propelled vehicle 13—a fragmentary portion only whereof is indicated as it forms no part of my invention. Appropriately seated on the platform or truck body 10 is a vertical or other steam generator 14 provided with flexible or other pipe connections 15 under the control of valves 16 for conveying live steam to the side and end snow reducers a , a^1 and a^2 , respectively as hereafter more fully explained.

Each of the reducers or snow melting devices a , a^1 , and a^2 , includes rectangular or appropriate cross section ends or headers 17, 17, connected together radiator fashion by parallel pipes 18, the undersides whereof are perforated with holes 19 for the emission of steam downwardly, and at each end of said reducers there is provided an outwardly and upwardly inclined shoe or scoop member 20. Freely rotatable wheels 21 are mounted on each header end so that the reducers can be traveled over the surface of the snow to be melted.

Attached to the underside of the aforesaid platform or truck body 10, are spaced stirrups or yokes 22, through which pass links 23 supporting anti-friction rollers 24 adapted to traverse the opposed and parallel vertical faces of said stirrups or yokes 22 and these links have pivoted at their outer ends 100 by pivot pins 25 downwardly curved members 26, the lower ends whereof are hingedly connected by pintles 27 between spaced upstanding lugs 28 on the headers 17. It is to be particularly noted that a curved 105 member 26 is connected to each header 17 of the side reducers a , a^1 , and that two such members 26 are similarly connected to the inner header 17 of the end reducer a^2 .

Appropriately connected to the outer pipe 110 18 of each side reducers a , a^1 , and to the outer header 17 of the end reducer a^2 , is a chain or cable 29 passing over or around guide pulleys or sheaves 30 and attached to

the drums 31 of an appropriate winding engine or windlass 32, each said drum 31 being adapted by appropriate clutch mechanism—not shown—for independent operation, or 5 all three drums may be simultaneously operated, as will be readily understood by those skilled in the art to which this invention appertains. Now it will be readily seen that by winding up all, or any one of the 10 chains or cables 29, all or the individual reducers a , a^1 , a^2 , may be raised from a substantially horizontal to an approximately vertical or inwardly inclined position relative to the platform or truck body 10, said 15 reducer or reducers swinging on the pintles 27 as pivots. Still further it is to be noted that the aforesaid links 23 and curved members 26, are formed with abutments 33 to constitute what may be termed a limiting 20 hinge connection so that when said parts 23, 26, are in the position shown in Figure 3, any binding tendency of the rollers 24 is offset or prevented.

In some instances it may be preferable 25 to make provision for raising the inner parts of the reducers a , a^1 , a^2 , so that said headers may be downwardly inclined shovel fashion or so disposed to dig into a snowbank or drift and to this end I provide an auxiliary winding 30 engine 34 having drums 35 over which pass cables or chains 36 connecting with the inner pipes 18 of the side reducers a , a^1 , and the inner header 17 of the end reducer a^2 . Thus it will be readily seen that by operating one 35 or other or all of the drums 35, the connected reducer or reducers a , a^1 and a^2 can be raised sufficiently to incline said reducer or reducers as indicated by the dot and dash lines at the right hand of Figure 2, or in 40 other words have the outer end or side downwardly inclined into the snow bank or drift and then by allowing the inner end to gravitate downwards the reducer or reducers will be forced beneath said bank or drift which 45 results in the rapid conversion of the superincumbent snow into water by direct contact with the heated surfaces of the pipes 18.

Obviously the machine may be employed 50 for removing ice coatings from the surfaces of streets, sidewalks, and highways just as effectively as has been described for reducing snow.

From the foregoing description taken in conjunction with the accompanying drawings 55 the numerous merits and advantages of my invention will be self-evident, whilst its adaptation for attachment to a work car for street railways or for use on railroads as a snow plough; or its transportation by 60 animal or other power will be readily understood without further detailed description.

Whilst I have described and shown one convenient embodiment of my invention it will be clearly seen that many changes in

the details of construction, combination and 65 arrangement of the several parts could be effected without departing from the spirit and scope thereof, and it is hereby intended to include all such changes and reasonable modifications as fairly fall within the scope 70 of the appended claims.

Having described my invention what I claim as new and desire to secure by Letters Patent, is:—

1. In a machine of the type described the 75 combination of a transportable vehicular body, hollow frames hingedly suspended from the body by vertically slideable hinge members adapted to hold said frames in substantially horizontal planes, means for 80 swinging the hollow frames into substantially vertical position, supplementary means for raising said hollow frames into downwardly inclined position relative to the transportable vehicular body, and means 85 for generating and supplying live steam to the hollow frames for emission downwardly onto the surface over which the machine is traveled.

2. In a machine of the type described the 90 combination of a transportable vehicular body, hollow frames hingedly suspended from the body by vertically slideable hinge members adapted to hold said frames in substantially horizontal planes, means for 95 swinging the hollow frames into substantially vertical position, supplementary means for raising said hollow frames into downwardly inclined position relative to the transportable vehicular body, means for 100 generating and supplying live steam to the hollow frames for emission downwardly onto the surface over which the machine is traveled, and means carried by the hollow frames for deflecting part of the material 105 on to the upper surfaces thereof for reduction by heat radiation.

3. A snow removing and reducing machine comprising in combination, a transportable vehicular body, hollow frames 110 hingedly suspended from the body by vertically slideable hinge members adapted to hold said frames in substantially horizontal planes, means for swinging the hollow frames into substantially vertical position, 115 supplementary means for raising said hollow frames into downwardly inclined position relative to the transportable vehicular body, means for generating and supplying live steam to the hollow frames for emission 120 downwardly onto the surface over which the machine is traveled, and means carried by the hollow frames for deflecting part of the material on to the upper surfaces thereof for reduction by heat radiation. 125

In testimony whereof I affix my signature.

ELBERT E. RICKS.
